UNITED STATES PATENT OFFICE

2,382,954

OSCILLATOR

Serge Beaudoin, St. Joseph, Quebec, Canada

Application November 10, 1943, Serial No. 509,721

6 Claims. (Cl. 250—36)

The present invention pertains to a novel vacuum tube oscillator. The principal object is to provide an oscillator of improved frequency stability.

This object is accomplished by means of a pair of inductively coupled coils, of equal inductance connected respectively to the cathode and grid and without forming a parallel circuit with the tube. The manner in which the device functions to produce the desired result is set forth in the following description.

The invention is fully disclosed by way of example in the following description and in the accompanying drawing in which:

Figures 1, 2 and 3 are diagrams of three different circuits according to the invention.

Reference to these views will now be made by use of like characters which are employed to designate corresponding parts throughout.

In Figure 1 is shown a pentode 1 including a cathode 2, and anode 3 and three grids 4, 5 and 6. The anode, cathode and grids may be charged in any suitable manner. For example, the anode 3 and grid 5 are connected to positive potentials 7 and 8. Connected to the grid 5 is a bleeder comprising a series resistor 10 with a shunt condenser 11, the resistor being grounded at 12 and tapped at 13.

The grid 4 is grounded at 13. The grid 6 is connected as will presently be described.

Oscillation is produced through a pair of inductively coupled coils 14, 15 of equal inductance and connected respectively to the cathode 2 and the grid 6 at 17 and 18. In the connection 18 may be provided a grid leak consisting of a series condenser 19 and a shunt resistor 20. Both coils are grounded at 21 and 50, and the coil 14 may be connected in series to a resistor 22 having a shunt condenser 23 for polarization of the grid through the cathode.

Coupled to the coils 14, 15 at the connections 17, 18 are a pair of ganged or synchronized variable condensers 24, 25 having equal capacity and the same charging curve. Both are grounded at 26, 27.

In operation, the oscillation is maintained by the cathode and acts on the grid through the self-inductances. The cathode-grid oscillation being in tune, the tube will oscillate at a frequency determined by the inductances. This oscillator has a much higher stability than the conventional oscillators, such as the Hartley circuit. The higher stability is attributed to the series, rather than parallel, relation of the inductances to the tube. Further, the variations in the ca-

pacity of the several electrodes relatively to the chassis, caused by voltage variations applied to these electrodes, do not influence the inductances. Since the latter control the frequency of oscillation, the oscillation remains stable in spite of feeding variations. For a greater efficiency, the polarization device 22, 23 is used as shown in Figures 1 and 2.

In the embodiment shown in Figure 2, the polarization device has been eliminated, and both inductance coils 32, 33 are connected to a common ground 34. This device lends itself more readily to change of band.

Figure 3 shows a triode with a cathode 35, plate 36 and grid 37. The inductance coils 42, 43 have a common ground 44, and the ganged condensers 45, 46 are connected in parallel respectively with the coils.

The stability of oscillation is due mostly by the inductance of the cathode which is in series with the tube.

In stability of oscillation, this system compares favorably with the crystal and has the advantage of a variable frequency. The change of frequency requires a two-circuit switch, however the device is no more complicated than, for example, the Hartley circuit.

Although specific embodiments of the invention have been illustrated and described, it will be understood that various alterations in the details of construction may be made without departing from the scope of the invention as indicated by the appended claims.

What I claim as my invention is:

1. In an oscillating circuit, a vacuum tube having a cathode, an anode and a grid, a pair of inductively coupled coils of equal inductance connected respectively to said cathode and grid at one end and grounded at the other end, and a pair of ganged condensers connected respectively to said coils.

2. In an oscillating circuit, a vacuum tube having a cathode, an anode and a grid, a pair of inductively coupled coils of equal inductance connected respectively to said cathode and grid at one end grounded at the other end, and a pair of ganged condensers connected respectively in parallel with said coils.

3. In an oscillating circuit, a vacuum tube having a cathode, an anode and a grid, a pair of inductively coupled coils of equal inductance connected respectively to said cathode and grid at one end and grounded at the other end, and a pair of ganged condensers connected respectively

to said coils, and a polarization device connected to said cathode.

4. In an oscillating circuit, a vacuum tube having a cathode, an anode and a grid, a pair of inductively coupled coils of equal inductance connected respectively to said cathode and grid at one end grounded at the other end, and a pair of ganged condensers connected respectively in parallel with said coils, and a polarization device connected to said cathode.

5. In an oscillating circuit, a vacuum tube having a cathode, an anode and a grid, a pair of inductively coupled coils of equal inductance connected respectively to said cathode and grid at one end and grounded at the other end, and a pair of ganged condensers connected respectively in parallel with said coils, and a polarization device connected to said cathode.

one end and grounded at the other end, and a pair of ganged condensers connected respectively to said coils, a resistor in series with one of said coils, and a condenser in parallel with said resistor.

6. In an oscillating circuit, a vacuum tube having a cathode, an anode and a grid, a pair of inductively coupled coils of equal inductance connected respectively to said cathode and grid at one end and grounded at the other end, and a pair of ganged condensers connected respectively to said coils, and a grid leak between said grid and one of said coils.

SERGE BEAUDIOIN.
